Primary Examiner — Austin Murphy(74) *Attorney, Agent, or Firm* — Jacobson Holman, PLLC.(57) **CLAIM**

I claim the ornamental design for a feedback station with a backboard, as shown and described.

DESCRIPTION

FIG. 1 is a front perspective view of a feedback station with a backboard embodying my design;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is an exploded top plan view of FIG. 1; and,

FIG. 7 is a bottom view of FIG. 1.
